UNITED STATES PATENT OFFICE.

JOSEPH M. VAIL, OF BRYAN, OHIO.

COMBINED RAIL STAY AND BRACE.

No. 917,815.

Specification of Letters Patent.

Patented April 13, 1909.

Application filed October 21, 1908. Serial No. 458,769.

To all whom it may concern:

Be it known that I, JOSEPH M. VAIL, a citizen of the United States, and a resident of Bryan, in the county of Williams and State of Ohio, have invented a certain new and useful Combined Rail Stay and Brace; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to devices adapted to coöperate with railway-rails and their supporting ties to prevent longitudinal creeping of the rails and to laterally brace the same, or to perform either of such functions.

20 The object of my invention is the provision of a simple, strong, and efficient device of this class which is easy of application and adapted to serve either to prevent a creeping of the rail relative to an associated tie or to 25 brace the same against lateral stresses, or to perform both such functions.

The operation, construction and arrangement of the parts of the invention are fully described in the following specification and 30 illustrated in the accompanying drawings, in which,—

Figure 1 is a top plan view of a portion of a rail and supporting tie with the device comprising my invention. Fig. 2 is a section 35 taken on the line x , x in Fig. 1; and Fig. 3 is a side elevation of a rail with my invention associated therewith and the tie in cross-section.

Referring to the drawings, 1 designates a 40 rail and 2 a tie upon which the rail is supported. Extending across the under side of the rail-base is a clamp-bar or yoke member

3, which is provided at one end with an upwardly and inwardly turned hook 4 45 adapted to engage over one edge of the rail-base, as shown. The opposite end of the bar 3 is provided with an upwardly projecting lug or boss 5, which is spaced from the contiguous side of the rail-base and has its 50 inner face tapered horizontally or relative to the rail-base. Carried by the bar 3 between the rail-base and tapered-faced lug 5 is a wedge-block 6, which is intended to co-operate with the lug 5 to firmly grip the rail-base in opposition to the hook 4 to hold the 55 bar 3 thereto.

The wedge-block 6 is shown as having its top forwardly inclined, as at 7, and as being provided therethrough with a laterally broadened opening, as shown by dotted lines in Fig. 3, for receiving the shank of a clamping-bolt 7, which passes through a registering aperture in the bar 3, said aperture having its axis disposed at right-angles to the inclined top of the wedge-block. The purpose of inclining the top of the wedge-block and disposing the bolt 8 at an incline relative to a vertical is to cause the wedge-block to have a tendency to move forward to more tightly grip the rail-base when the bolt is tightened. I wish it understood, however, that I do not desire to be restricted to the use of any particular means for securing the wedge-block to its bar, as this may be done in numerous ways.

The bar 3 preferably, but not necessarily, has its inner or tie-coating side made straight and is provided on such side near its wedge-block carrying-end with a spur or tenon 9, which is intended to be driven into the side of the tie to secure the bar against longitudinal movement. In driving this spur into a tie the opposite end of the bar is held slightly spaced from the tie side so that only the spur carrying end of the bar abuts against the tie when the spur is driven home. The purpose of this is to cause the resistance of a tie to any creeping strain of the rail to be exerted on the bar 3 at such end, so that the wedge-block 6 will have a tendency to slip relative to the lug 5 whereby to more tightly grip the rail-base rather than to slip relative to the rail. To further carry out this idea I provide anti-friction balls 10 between the coating faces of the lug 4 and wedge-block 6, said balls being mounted in pockets provided in the inner face of the lug, as shown by dotted lines.

For the purpose of adapting the wedge-block to serve as a rail-brace, the inner upper edge thereof is continued over the contiguous side of the rail-base and vertically broadened to form a wing or enlargement 11, which abuts against the side of the rail-web and the under side of the rail tread or head, as shown. Projecting from the forward end of the wedge-block 6 is an arm 12, which is angled outwardly relative to the rail 1 and rests on the top of the tie with which the bar 3 abuts, thus causing the tie and wedge-block to act together to brace the rail. It is thus apparent that my device provides a simple, strong

and very efficient means for bracing a rail against lateral stresses in addition to serving as a stay to prevent a creeping thereof relative to the associated tie.

5 I desire it to be understood that my invention is not limited to any specific form or arrangement of parts except in so far as such limitations are specified in the claims.

Having thus described my invention, 10 what I claim as new and desire to secure by Letters Patent, is,—

1. A device of the class described, comprising a clamp-bar adapted to underlie a rail-base at the side of a tie and having a rail-flange engaging hook at one end and a lug at the other end, a member adapted to coöperate with the lug and hook to firmly grip the rail-base and having portions adapted to coact with the rail web and a tie to brace the 15 former, and means for securing said member to the clamp-bar.

2. A device of the class described, comprising a clamp-bar, a wedge-block adapted to coöperate with said bar to grip a rail-base, 20 said block having a portion adapted to project over the contiguous rail flange and abut against the rail-web and the under side of the

rail-head and a portion projecting from its forward end at an angle to the rail for bearing upon the top of a tie, and means for securing 30 the wedge-block to the clamp-bar.

3. The combination with a rail-stay clamp-bar and the wedge-block carried thereby, of antifriction means between the abutting faces of the clamp-bar and wedge-block which are 35 opposed to the rail engaging side of the block.

4. In a rail-stay, a clamp-bar having a rail-flange engaging hook at one end and a wedge-coacting lug at the other end, a wedge-block adapted to abut against said lug and to co-operate with the clamp-bar to grip a rail-base, anti-friction means disposed between the coacting surfaces of the lug and wedge-block, and means for preventing an outward movement of the wedge-block relative to the 45 clamp-bar.

In testimony whereof I have hereunto signed my name to this specification in the presence of two subscribing witnesses.

JOSEPH M. VAIL.
